Primary Examiner — Jennifer L Rempfer*Assistant Examiner* — Salamah Jordan(74) *Attorney, Agent, or Firm* — Muncy, Geissler, Olds & Lowe, P.C.(57) **CLAIM**

The ornamental design for a elliptical exercise machine, as shown and described.

DESCRIPTION

FIG. 1 is a front elevational view of a elliptical exercise machine showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a perspective view thereof; and,

FIG. 8 is an enlarged view of the encircled portion ‘8’ in FIG. 3.

The broken lines shown in the drawings are for the purpose of illustrating portions of the article and form no part of the claimed design.

1 Claim, 8 Drawing Sheets(56)
